SNOW AND ICE MELTING MACHINE

Anthony Fiduccia, Cedar Grove, N. J.

Application January 7, 1948, Serial No. 884

3 Claims. (Cl. 126—343.5)

1

This invention relates to snow and ice melting machines in general.

Among the objects of the present invention, it is aimed to provide an improved snow and ice melting machine for use in cleaning streets and the like, characterized by a heating mechanism not only for melting the snow and ice fed thereto, but also to heat the water resulting from the snow and ice so as to maintain the same in a liquid state ready to be discharged into a sewerage conduit or the like.

It is still another object of the present invention to provide a heating medium which will produce an extended flame to be directed at a temporary ice and snow holder and which can be directed into a flue or conduit passing through the water receiving chamber below the upper level of the water so received to maintain the water at a low enough temperature to facilitate its discharge into a sewerage conduit or other waste water receiver.

These and other features, capabilities and advantages of the present invention will appear from the subjoined detail description of specific embodiments thereof illustrated in the accompanying drawings, in which

Fig. 1 is a plan view.

Fig. 2 is a section on the line 2—2 of Fig. 1.

Fig. 3 is a section on the line 3—3 of Fig. 1.

Fig. 4 is a side view enlarged and partly in section of a burner unit.

Fig. 5 is a diminished fragmental cross section showing another type of trough.

In the embodiment shown there are illustrated two supporting U-beams 1 and 2 having supported thereon a platform 3, which beams 1 and 2 and platform 3 may be part of a truck or the like conveyance or other support. On this platform there is mounted a tank 4 having a base 5, two end walls 6 and 7 and two side walls 8 and 9.

Preferably in the rear end wall 6 there are provided two openings, one opening 10 adjacent the base 5, and the other opening 11 preferably a little below the middle of the tank 4. The opening 10 is preferably provided with the closure cap 12, normally closed but available to be opened in order to drain the tank 4 and clean the same, since frequently the snow and ice removed from the street may have mixed with it refuse, branches of trees and the like which may drop into the tank with the water resulting from melting the snow and ice as hereinafter to be described. The opening 11 in turn is provided with a nozzle 13 to receive the coupling 15 of the hose 14. The opening 11 is located at a predetermined level of

2

the waste water in the tank 4 to act as an overflow. The hose 14 may be of any suitable length and preferably flexible to enable the attendant to direct the overflow to the inlet of a sewer or other waste water receiver.

For receiving the snow and ice to be melted and disposed of as water, there is provided a hopper 16 formed by the downwardly and inwardly inclined walls 17, 18, 19 and 20. The inner lower ends of the walls 17, 18, 19 and 20 in the present instance have inwardly extending flanges 21 to serve as supports for the rectangular angle iron frame 22 of the trough 23, preferably composed of a suitable foraminous material or wire mesh. This trough 23 in the present instance has triangular wire mesh end walls 24 and 25 and two inclined side walls 26 and 27 connected to the end walls and connected to one another at their lower adjacent ends, to form a substantially triangular trough in cross-section, see Fig. 3.

Above the level of the water in the tank 4, and approximately in alignment with the trough 23, the rear wall is provided with a rectangular opening 28, see Fig. 3, to facilitate inspection, insertion and removal of the trough 23 and also to provide an adequate inlet for air to facilitate combustion.

The front wall 7, on the other hand, preferably has a narrower opening at the upper end, such as the opening 29, to serve as a discharge for products of combustion, as an instance.

The side walls 8 and 9 are also each provided with an elongated opening, see the openings 30 and 31 substantially in alignment with the trough 23 to serve not only as inlets for air to supplement the air supply passing through the opening 28, but also to clear the burner units 32 and 33 mounted on the platforms 34 and 35, respectively.

The platforms 34 and 35 are, as shown in Fig. 3, suitably secured to the upper edges of the wall portions 8 and 9 at the lower ends of the openings 30 and 31, respectively. These platforms 34 and 35 preferably extend a short distance into the tank 4.

The burner units 32 and 33, see Fig. 4, each consist essentially of a pan 36, an outer integral housing element 37 secured to the pan 36 and extending upwardly therefrom, a forwardly extending cylindrical perforated extension 38 connected to the housing element 37, a burner nozzle 39 disposed at the outer entrance end of the extension 38 and a fuel supply conduit 40 connected to the control valve 41. The conduit 40 preferably has a portion 42 extending from the valve 41 into the housing 37 and connected to the lower end of the platform or bracket 43 connect-

ed to the housing 37. From the platform 43 the conduit 40 extends downwardly into the pan 36, see the portion 44, and then back up into the cylindrical extension 38 in the form of a coil 45 and from the coil portion 45 to the nozzle 39. The nozzle 39 preferably, as shown in Fig. 4, is mounted upon the platform 43. The pans 36 preferably have ears 46 extending from the sides thereof to receive the wing nuts and bolts 47 which pass through the slots 48 in the platforms 34 and 35 whereby the burner units 32 and 33 may be adjusted relative to the trough 23. Preferably the platforms 34 and 35 are provided with the conduits 49 and 50, respectively, secured to the lower faces thereof, one end of the conduit 49 being connected by the flexible conduit 51 with the discharge end 52 of the fuel supply tank 53 and the conduit 50 being connected by the flexible conduit 54 with the discharge end 55 of the fuel tank 56. The conduits 49 and 50 in turn are provided with outlets to receive the flexible conduits 57 which in turn are connected to the valves 41 of the burner units 32 and 33. The conduit 49 is also provided with a connection for the flexible conduit 58 connected to the valve 59 of the burner unit 60 mounted on the platform 61, and in turn the conduit 50 is provided with a connection for the flexible conduit 62 which is connected to the valve 63 of the burner unit 64 mounted on the platform 65. The burner units 60 and 64 are substantially identical to the burner units 32 and 33, and therefore the description of the burner unit illustrated in Fig. 4 will be relied upon to suffice as a description of the burner units 60 and 64.

The burner units 32 and 33 are so positioned on the platforms 34 and 35 that the flames produced by the nozzles 39 thereof will extend to and be directed at, and through, the trough 23 at a level above the lower end thereof.

In this way the entire mesh of the trough 23 will be heated, the lower end of the trough 23 in part by conduction.

The burners 60 and 64, on the other hand, are positioned to direct the flames produced by their nozzles 39 into the conduits 66 and 67, respectively. The conduit 66 extends across the rear end of the tank 4 below the upper level of the water, and then extends forwardly to the upward extension 68. The conduit 67, on the other hand, extends across the tank 4 at the rear end thereof at a level slightly below the conduit 66, and then forwardly to the upward extension 69. The upper ends of the upward extensions 68 and 69 are exposed, that is open, and positioned in alignment with the lower end of the front opening 29 in the wall 7 of the tank 4, so that the hot air and gas generated by the flames directed into the conduits 66 and 67 will escape from the upper ends of the extensions 68 and 69 through the opening 29 into the atmosphere.

In this way one and the same fuel medium can be used for generating heat in the conduits 66 and 67 to maintain the water in the tank 4 at least, above freezing where it can readily be discharged through the over-flow pipe 14 and preferably high enough to melt any snow that might drop through the trough 23, and also supply the fuel for the flames which are directed by the burner units 32 and 33 at the inclined mesh walls 26 and 27 of the trough 23.

Excellent results have been achieved when the fuel in the fuel tanks 53 and 56 was ordinary kerosene fuel compressed by the hand controls

70 and 71 to pressures averaging between twenty-five to thirty pounds.

When ordinary kerosene fuel is used, then with burners of this type it is common practice initially, see Fig. 4, to pour a prime supply in the pans or wells 36, light the same and thereby heat the conduits 40 and coils 45. When these conduits have been heated sufficiently, then the valves 41 are opened and the initial gas escaping from the nozzles 39 will be automatically ignited from the flames of the burning kerosene in the pans 36.

Excellent results have also been achieved when the burner units 32 are staggered relative to the burner units 33, see the arrangement in Fig. 1, and also when the metal of the wire mesh of the trough 23 was composed of case hardened steel metal which would admirably withstand the heat without deterioration of the metal, so long as care was exercised to see that the trough 23 was filled with snow or ice before the gas issuing from the nozzles 39 was ignited. The flames issuing from the nozzles 39, both of the burner units 32 and 33, as well as of the burner units 60 and 64 gave excellent results when the pressure was sufficient to produce a flame of about twenty-four inches in length. Under some circumstances these flames could be increased to lengths of forty-two inches, depending upon the temperature, with excellent results. Since the width of the tanks from wall 8 to wall 9 is about forty-eight inches, the staggered relation, of course, will enable the flames from the two sets of burner units 32 and 33 effectively to be distributed the full length of the trough 23, and by virtue of the length of the flames effectively cross the trough 23. The location of the point of contact of the flames from the burner units 32 and 33 on the trough 23 about midway between the lower apex of the trough 23 and the frame 22 is also of value in preserving the metal from deterioration, the heat, according to heat phenomena, dissipating in part from the lower apex of the trough 23 and the snow, even though only momentarily accumulated in the apex, reducing the temperature in the metal sufficiently to preserve it from injury.

It will also be noticed that the hopper formed by the walls 17, 18, 19 and 20 is sufficiently deep, about thirty-inches, so that it may receive a substantial load for effective and expeditious removal of snow and ice when a conveyor or the like is used to feed the snow and ice to the hopper. The upper edges of the walls 6, 7, 8 and 9 of the tank to which the walls 17, 18, 19 and 20 of the hopper are connected also support the flange extension 72. This flange extension 72 surrounds the upper edge of the hopper and tank and extends sufficiently outward at least to cover the burner units 32 and 33, in part to protect the burner units from snow and ice during inclement weather. Furthermore, to more effectively protect the same, the edges of the side portions of the flange extension 72 have pivotally connected thereto the extended panels 73 and 74 by the hinges 75 and 76, respectively, and the lower edges of the panels 73 and 74 in turn have hingedly connected thereto the secondary panels 77 and 78, respectively, by the hinges 79 and 80, respectively. These secondary panels 77 and 78 are recessed at 81 and 82, respectively, to clear the conduits 40.

It is, of course, obvious that the level of the water in the tank 4 must be maintained below the burner units 32 and 33 so that these burner units

may not be extinguished by the water overflowing onto the same.

While flames of various intensity may be used it may be noted that excellent results have been achieved when these flames have an intensity of about 2000 E. t. u. per minute.

In the embodiment shown in Fig. 5, the side and end walls 83 of the hopper are considerably shorter than the side and end walls 17, 18, 19 and 20 of the hopper illustrated in Figs. 2 and 3, and the trough 84 is considerably deeper as compared to the trough 23 of the first embodiment.

It is obvious that various changes and modifications may be made to the details of construction without departing from the general spirit of the invention as set forth in the appended claims.

I claim:

1. The combination of a tank having a water containing lower section, a hopper secured to the upper end of said tank to receive snow and/or ice, a wire mesh trough at the lower end of said hopper, a plurality of horizontally arranged burners for directing flames at said trough, conduits located in said lower section of the tank below the water level, and burners in communication with the entrance ends of said conduits to direct flames into the same, there being an opening adjacent the upper end of said tank, the outlet ends of said conduits being disposed above the water level and adjacent the opening in the upper end of said tank to facilitate discharging gases of combustion and hot air therethrough, the trough being triangular in cross section with the apex at the bottom and disposed below the level of the flames of said horizontally arranged burners.

2. The combination of a tank having a water containing lower section, a hopper secured to the upper end of said tank to receive snow and/or ice, a wire mesh trough at the lower end of said hopper, a plurality of horizontally arranged burners

5 for directing flames at said trough, conduits located in said lower section of the tank below the water level, and burners in communication with the entrance ends of said conduits to direct flames into the same, there being an opening adjacent the upper end of said tank, the outlet ends of said conduits being disposed above the water level and adjacent the opening in the upper end of said tank to facilitate discharging gases of combustion and hot air therethrough, horizontally extending flanges extending outwardly from the upper edges of said hopper over said horizontally arranged burners, and panels hingedly connected to said flanges effectively to cover said burners during inclement weather.

10 3. The combination of a tank having a water receiving lower section, a hopper secured to the upper end of said tank to receive snow and/or ice, a wire mesh trough at the lower end of said hopper, and a plurality of horizontally arranged burners for directing flames at said trough, the trough being triangular in cross section with the apex at the bottom and disposed below the level of the flames of said horizontally arranged burners but above the level of the water in said water receiving lower section.

15 ANTHONY FIDUCCIA.
